UNITED STATES PATENT OFFICE.

EWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed January 27, 1927. Serial No. 163,988.

My invention relates to ribbon mechanism for typewriting machines and has for its main purpose the provision of means for controlling the ribbon spools in relation to their supports and for improving certain of the devices associated with said spools.

The invention was particularly designed as an improvement on the ribbon mechanism of the Remington Portable typewriting machine, but its principles may readily be adapted to other styles of writing machines. In said Remington Portable machine the ribbon spools are horizontally disposed being mounted on vertical pins or spindles, the ribbon being adapted to be fed from one spool to the other by mechanism for turning the spools. Associated with the ribbon feeding mechanism is ribbon reversing mechanism whereby the direction of ribbon feed may be reversed, said reversing mechanism comprising a pair of so-called pivoted "trailers" or followers, each follower having a portion cooperative with the plies of ribbon wound on its spool in such a way that when the ribbon on one spool has been exhausted the associate follower is moved to a position where its actuating pin will become effective to move the ribbon driving shaft longitudinally to change gears and disconnect the associate spool, at the same time connecting the other spool with the driving shaft all in a manner well understood. Trouble has heretofore arisen from the engagement of the follower with the ribbon plies during a removal and a replacement of the spool from its support and my present invention has for one of its objects to avoid such trouble, this being done by providing the follower with a special finger-piece which in the present instance serves several purposes. In the first place the finger-piece, being disposed so as normally to directly overlie the associate spool, will prevent an upward movement of displacement of the spool under normal conditions, it being necessary to swing the handle and with it the follower to a position outside of the spool before the latter can be removed. Likewise in replacing the spool it will be necessary to swing the finger-piece out of the way and with it, of course, the follower, in order to clear the path for the spool. The finger-piece further serves as a pointer or visual indicator for the follower.

To the above and other ends which will hereinafter appear, my invention consists in the features of construction, combinations of

devices and arrangements of parts herein-after described and particularly pointed out in the claims.

My invention will be described in detail in connection with the accompanying drawing, 60 wherein—

Fig. 1 is a fragmentary front elevation showing a ribbon spool, its mounting and associate parts.

Fig. 2 is a perspective view showing one of 65 my improved ribbon controlling member or follower devices.

Fig. 3 is a fragmentary plan view showing the ribbon spools and the ribbon feeding and reversing mechanism. 70

Fig. 4 is a perspective view of a detachable support for the ribbon controlling member or follower.

Fig. 5 is a side view of a ribbon spool showing the ribbon attaching devices applied thereto; and 75

Fig. 6 is a perspective view of a ribbon attaching device.

The Remington Portable typewriting machine to which my invention is shown as applied is provided with a key-controlled shiftable frame which comprises side plates or portions, the left-hand side plate only being shown herein (Fig. 1) and designated by the numeral 1. Integral with the side plate 1 is an 80 angularly bent-off portion or ear 2 which provides a support for a cylindrical bearing member or block 3 from which rises a post or bearing pin 4. Supported on the cylindrical block 3 and rotatable on the pin 4 is a circular 85 plate 5 rigid with which is a crown gear wheel 6, the wheel being disposed below the plate 5 and its teeth being adapted to mesh with the teeth of a beveled pinion 7 secured to a ribbon driving shaft 8 that extends transversely of the machine and bears rotatively on the bearings 3. It will be understood that the construction above described, including the parts or elements 2 to 6 inclusive, although fully illustrated only for the left-hand side 90 of the machine, is duplicated at the right-hand side, and that the shaft 8 bears two pinions 7 which are so disposed that they are adapted to mesh alternatively with their associate gear wheel 6, the shaft 8 being movable back and forth endwise for this purpose. The shaft 8 is adapted to be rotated automatically when the printing keys are actuated, the means for turning the shaft comprising a ratchet wheel 9 fixed thereto at about its middle as shown 100 105 110

in Fig. 3. Cooperative with the ratchet wheel is a driving pawl 10 actuated from the printing keys and a holding pawl 11. The shaft 8 may be moved endwise by hand and is also 5 rotatable by hand, knurled finger buttons 12 being secured at the opposite ends of said shaft for these purposes. Integral with the finger buttons 12 are double cam members 13 which are comprised in the ribbon reversing 10 mechanism. The pawls 10 and 11 are of sufficient width to cooperate with the ratchet wheel 9 in both positions to which it may be shifted when the shaft 8 is moved endwise.

Each of the circular plates 5 provides a 15 support for a detachable ribbon spool or rotary carrier, said spool as best shown in Fig. 5 comprising essentially a core or hub portion 14 and parallel circular heads or flanges 15 secured at opposite ends of the core or hub. 20 The core is formed with a circular bore to fit over the associate pin or bearing post 4. Projecting downward from the lower flange are two diametrically opposite lugs or tits 16 which are adapted to engage in a slot or depression formed in the underlying plate 5, thereby connecting the spool with the plate so that when the plate and its gear 6 are rotated the spool or ribbon carrier will likewise be rotated, the pin 4 providing a support and bearing for the spool. 25

The ribbon 17 is attached at its opposite ends to the ribbon spools 14, 15 and is adapted to be wound on said spools alternately. There is provided preferably an improved 30 and simplified means of attaching the ribbon at its end portions to the spool cores. Said means comprises spring clips one of which is shown detached in Fig. 6 and numbered 18. The clip is made of a single piece 40 of sheet metal bent or formed in the arc of the circle and of such size as to fit over and embrace the core piece 14 between the spool flanges 15. The clip fits somewhat more than halfway around the core so that when it has 45 been sprung into place thereon it will engage or clip the core by reason of its inherent friction and some force is necessary to detach it, thereby guarding against accidental displacement. Preferably a point or arrow 50 19 is struck out of the body of the clip and bent so as to stand slightly away therefrom. This point or arrow is thrust through the end portion of the ribbon, thereby attaching it to the clip so that when the clip is 55 applied to the core the ribbon is thereby attached to the ribbon spool and when the spool is turned the ribbon will be wound on the core piece between the spool flanges or heads.

It will be understood that when the printing keys are actuated their motion will be transmitted to the pawl 10 in the usual way, said pawl actuating the ratchet wheel 9 and turning the driving shaft 8 together with the driving pinions 7. One of these pinions 60 will be idle or disengaged and the other will

be engaged with its associate gear wheel 6, so that the turning movement of the shaft is transmitted to the engaged gear wheel and circular plate 5, and thence to the ribbon spool mounted on said plate, the spool being turned to wind the ribbon thereon, the ribbon being drawn off the free or loose ribbon spool at the opposite side of the machine. It has not been deemed necessary to show the ribbon driving mechanism in full nor the ribbon 70 vibrating mechanism whereby the printing portion of the ribbon is interposed between the type bars and the platen at each printing stroke, but these mechanisms are of the usual construction found in the Remington Portable typewriter. 75

The ribbon reversing mechanism in addition to the double cam members 13 comprises devices cooperating with said members to shift the driving shaft 8 automatically back and forth as the ribbon spools are alternately emptied and filled. The cooperating devices aforesaid are in the form of ribbon controlling members each designated as a whole by the reference numeral 20. As clearly shown in Fig. 2, the member 20 is preferably formed of a single piece of sheet metal bent to the required shape. Said member comprises three horizontally disposed portions 21, 22 and 23 connected by vertical portions 24 and 25. Bent off from the cross portion 22 is an angular part or arm 26 terminating in a vertical extension 27, the parts 26, 27 constituting a so-called "trailer" or follower proper that is adapted to contact directly with the plies of ribbon wound on the associate ribbon spool and bearing inwardly against the outermost ply. Suitably secured to the upright portion 25 is a horizontal pointed pin 28 which is adapted to cooperate directly with the associate double cam 13. As thus far described the ribbon controlling member or follower 20 generally resembles the one heretofore employed. In order to carry out the purposes of the invention there has been added a special finger piece or handle 29 which projects horizontally from the uppermost horizontal portion 21 and is substantially parallel with the arm 26. 100

The three parallel horizontal portions 21, 110 22 and 23 are formed with round bearing openings 30 in register with each other, whereby the follower is adapted to fit on an upright post or pin 31 having a head 32 and fitted into and secured at its foot in an angular bracket 33 as most clearly shown in Fig. 4. The bracket 33 is provided with an angular upright extension 34 which is formed with a hole 35 to receive the shaft 8. The follower 20 is secured in place on the bearing post or pin 31 before said pin is assembled with the bracket 33, so that the bracket and follower are detachable from and replaceable on the machine together. The head 32 prevents upward displacement of the follower 115 120 125 130

while allowing it to turn freely on the pin. The base or foot portion of the bracket 33 is formed with elongated holes or slots indicated at 36, which slots receive headed screws 37 threaded into the associate ear or shelf-like part 2, whereby the bracket is adjustably secured to said ear. A coiled draw spring 38 is connected at one end to the upright portion 25 of the follower, said spring 10 at its opposite end being hooked through a hole in the upright portion 34 of the bracket. The spring tends constantly to hold the follower head or contact 27 in contact with the ribbon plies wound on the associate spool. 15 The part 29 of the follower overlies the upper flange 15 of the associate spool, under all normal conditions, and is so disposed vertically that while out of immediate contact with said flange, it will nevertheless be engaged by the flange on a very slight upward movement of the spool along its support or spindle 4. This will be clearly understood from a consideration of Figs. 1 and 3. From these views it will be apparent that not only 20 will the part 29 prevent upward displacement of the spool but it also acts as a visual indicator of the position of the follower and especially of the relationship of the follower head with the spool axis and flanges. As is 25 well understood, the spring pressed follower swings in on its axis or pivot 31 as the quantity or number of plies of ribbon wound on the spool lessens, the result of this pivotal swinging being that the pin or actuator 28 is 30 brought nearer and nearer to the path of movement of the associate cam member 13. The parts are so related that when the end portion of the ribbon is reached the actuating pin 28 will engage with the associate cam 35 and as a result will as the rotary movement of the shaft 8 continues force said shaft to move also longitudinally. Completion of the endwise movement is achieved as is well understood and effects an engagement of the 40 underlying driving pinion 7 with the associate gear wheel 6, the result being that the pay-off or idle spool will be connected with the driving mechanism to be positively driven in reversed direction when the printing keys 45 are actuated so as to wind the ribbon thereon. Fig. 3 shows the position of the parts immediately after the shaft 8 has been shifted endwise from left to right, thus disconnecting from the left-hand spool and connecting 50 with the right-hand spool.

It will be understood that the device or part 29 must be swung outward in order to allow the associate ribbon spool to be lifted from its post or spindle 4 and removed from 55 the machine. This swinging movement of the part 29 of course actuates the member or follower as a whole and withdraws the follower proper 26, 27 from between the flanges of the spool so that said spool is free to be 60 lifted from the machine. Likewise it will be

apparent that, with the spool off, it will be impossible to reapply it to its post or bearing, or to apply a new spool thereto, without first swinging the part 29 out of the way of the spool flange, this movement, of course, also 70 swinging the follower 26, 27 itself out of the way. In other words, the part 29 will operate to safeguard the follower so that it will be impossible, as sometimes has happened heretofore particularly when a one-flange 75 spool was employed, to improperly engage with the ribbon plies or to be distorted or bent out of place by the ribbon plies or by the spool itself should undue force be used by the operator. It will be appreciated that 80 distortion of the follower results in improper timing of or disablement of the ribbon reversing mechanism, and that it is consequently of primary importance to prevent such distortion. Such prevention is a result which 85 the present invention achieves. It will be seen then that the invention provides means which is most conveniently located for serving as a handle to manipulate or adjust the follower 20 and which further serves as a 90 safeguarding device to prevent improper handling of the spool and fouling of the follower, as well as serving to indicate to the eye the position of the follower device.

The downward extension 21^a may also be 95 used as a finger-piece for the follower, if desired.

Various changes may be made without departing from my invention.

What I claim as new and desire to secure 100 by Letters Patent, is:—

1. In a typewriting machine, the combination of a ribbon spool, a support which detachably receives said ribbon spool, a ribbon feed controlling member between the spool 105 flanges, and means rigid with said member and outside of the spool for normally preventing the removal of said spool from its support.

2. In a typewriting machine, the combination of a ribbon spool, a support therefor, a ribbon feed controlling member between the spool flanges and means rigid with said member and outside of the spool for normally preventing the removal of said spool from its 115 support, said member being movable by hand to render said means ineffective.

3. In a typewriting machine, the combination of a ribbon spool, a support therefor, a ribbon controlling member directly engaging 120 the ribbon on the spool, and a visual indicator rigid with said member and overlying the spool, said indicator showing when said member is in and out of working position.

4. In a typewriting machine, the combination of a ribbon spool, a support therefor, a ribbon controlling member directly engaging the ribbon on the spool, and a visual indicator rigid with said member and showing the position of said member, said indicator over- 125 130

lying said spool and also serving as a finger piece for manipulating said member.

5. In a typewriting machine, the combination of a rotary ribbon carrier, a support on which the carrier is adapted to rotate, a ribbon controlling member cooperative directly with the ribbon on said carrier, and a visual indicator rigid with said member and overlying said carrier, said indicator indicating 10 the relationship of said member with the ribbon.

6. In a typewriting machine, the combination of a horizontally disposed ribbon spool, a vertical spindle therefor, ribbon mechanism 15 including a ribbon controlling member cooperative with the ribbon on said spool, and a visual indicator adapted to overlie said spool and indicate the relationship of said member with the ribbon on said spool, said indicator being 20 also serving to prevent the spool from being lifted from its support and from being replaced on its support when said member is in working position, said indicator being movable at will without disturbing the ribbon mechanism as a whole to allow the spool to 25 be removed.

7. In a typewriting machine, the combination of a horizontally disposed ribbon spool, a vertical support therefor, a pivoted ribbon-controlling member cooperative with the ribbon on said spool, and a finger piece on said 30 member effective to swing it into and out of working position, said finger piece being adapted to overlie said spool to prevent its 35 being lifted on said support.

8. In a typewriting machine, the combination of a ribbon spool comprising a core piece and parallel flanges, ribbon reversing devices comprising a pivoted member providing a part disposed within said flanges and adapted constantly to contact directly with the ribbon wound on said core piece, said piv- 40

oted member being also provided with a finger piece for moving it into and out of working position, said finger piece lying outside 45 of and being adapted to contact with a flange thereof, said finger piece serving as a visual indicator to show the relationship of said part to the spool core and also serving as a preventive means for preventing displacement of the 50 spool on its support.

9. In a typewriting machine, the combination of a pair of ribbon spools each comprising a core and parallel flanges, pins on which 55 said spools are rotatable, ribbon feeding devices, ribbon reversing devices comprising a pair of pivoted followers adapted to co-operate with the plies of ribbon wound on the spools between their flanges, and finger pieces 60 for manipulating said followers, said finger pieces overlying said spools, preventing their being lifted on their pins and also preventing their being applied to said pins except when their associate followers are out of 65 working positions.

10. In a typewriting machine, the combination of a ribbon spool comprising a core and parallel flanges, a support on which said spool is detachably mounted, ribbon reversing mechanism comprising a device having 70 a follower arm disposed between the two flanges and cooperative with the ribbon wound on said spool core, and a finger piece rigid with said device and arranged outside and over the spool flanges for moving said 75 follower device into and out of working position, said finger piece, being substantially parallel with said follower arm and indicating the position thereof.

Signed at the borough of Manhattan, city 80 of New York, in the county of New York and State of New York, this 26th day of January, A. D. 1927.

EDWIN E. BARNEY.
